UNITED STATES PATENT OFFICE.

GEORGE L. BANKS, OF FREDONIA, KANSAS, ASSIGNOR TO CHARLES B. FARWELL, OF SAME PLACE, GEORGE CROOKE, OF CHICAGO, ILLINOIS, AND JOHN R. LEWIS, OF NEW YORK, N. Y.

RUNNING-GEAR FOR VEHICLES.

SPECIFICATION forming part of Letters Patent No. 453,533, dated June 2, 1891.

Application filed October 21, 1890. Serial No. 368,871. (No model.)

To all whom it may concern:

Be it known that I, GEORGE L. BANKS, of Fredonia, in the county of Wilson and State of Kansas, have invented a new and Improved 5 Running-Gear for Vehicles, of which the following is a full, clear, and exact description.

My invention relates to an improvement in running-gear for vehicles; and has for its object to provide a gear especially adapted for 10 use upon the bodies of carriages—such as buggies—so constructed that the springs need not be attached to the body, thus preserving them from the severe racking strain which such springs have usually to sustain.

15 A further object of the invention is to provide a means whereby the spring will have an independent end movement and at the same time preserve the body level sidewise.

The invention consists in the novel construction and combination of the several parts, as will be hereinafter fully set forth, and pointed out in the claims.

Reference is to be had to the accompanying drawings, forming a part of this specification, 25 in which similar figures of reference indicate corresponding parts in all the views.

Figure 1 is a bottom plan view of a wagon-body having the running-gear applied. Fig. 2 is a side elevation of the running-gear, the 30 springs being in section, and likewise the body of the vehicle. Fig. 3 is a transverse section through the springs and the forked bars, the section being taken practically on the line 3 3 of Fig. 2; and Fig. 4 is a plan 35 view of one of the forked bars used in connection with the springs.

Upon the under face of the vehicle-body 10 two sets of brackets 11 and 12 are secured, the set 11 being located near the rear end, 40 one at each side, and the other set near the forward end, also one at each side, of the body. The front set of brackets is slightly shorter than the rear set and the brackets are downwardly and forwardly curved, and the 45 rear set is curved to a practically semicircular shape and extends downwardly and rearwardly, as best illustrated in Fig. 2.

The rear axle 13 is provided with attached or integral blocks 13^a upon its front face, in

which a rock-shaft 14 is journaled, and at 50 the extremities of the shaft crank-arms 15 are formed pivotally connected with the lower extremities of the rear brackets 11 by links 16.

Blocks 17, corresponding to the blocks of the rear axle, are formed upon the rear side 55 of a bolster-bar 18, which is preferably provided with a concaved upper and a convexed lower face, and in the blocks 17 a forward rock-shaft 19 is journaled, provided at each end with a crank-arm 20, the said crank-arms 60 being pivoted directly to the lower extremities of the forward brackets 12.

The forward axle 21 is pivoted, by means of a king-bolt or its equivalent, to the under central surface of the bolster-bar, and is fitted 65 with any approved form of thill-sections 22, and the rear axle and bolster-bar are connected by diagonal strap-plates 23, which cross each other about centrally beneath the body, being attached at their point of contact. The extremities of the strap-plates are usually securely attached to the bolster-bar at or near its extremities and to the rear axle at a point near the blocks 13^a. At the crossing of the straps 23 a hanger 24 is fastened 70 provided with an aperture 25, and a downwardly-extending arm 26 is secured at the center of the rear rock-shaft, while an opposing arm 27 is likewise attached to the forward 75 rock-shaft.

Forked bars 28 and 29 are pivoted to the arms 26 and 27, one to each arm, and the bifurcated ends of the bars are so interlocked that one is capable of sliding between the members *a* of the other, as is best illustrated 85 in Figs. 2 and 3. The two interlocking bars pass through the aperture in the hanger 24. The pivotal ends of the bars are slightly twisted and provided with one or more additional pivot-openings 30, whereby the length 90 of the bars between the arms may be increased or decreased and the bars themselves act as a take-up. The interlocking bars are encircled by two coiled springs 31 and 32, one being located at each side of the hanger 24, 95 and the springs are held in place by bending the extremities of the bar members *a* to form lugs 23, extending at a right angle there-

from. The springs may be made more or less expansible by shortening the bars, and this may be accomplished either by changing their pivotal points or by upsetting more or less of the bifurcated extremities of the bars.

It is evident that in the presence of any weight in the body of the vehicle the action of the body upon the running-gear will be such as to draw outward the forked bars and compress the springs, which action will counteract any shock the occupant of the body of the vehicle would otherwise sustain when the vehicle is in motion. It is further apparent that the mechanism between the body and the springs will prevent the latter from receiving a sudden strain, thereby greatly adding to the durability of the springs, and although the springs are centrally located and capable of an independent end movement the structure connecting them with the body being very stable, and extending from front to rear of the latter, will not permit the body to sag sidewise.

Having thus described my invention, I claim as new and desire to secure by Letters Patent—

1. The combination, with forward and rear rock-shafts adapted to be pivotally connected with a vehicle-body and axles connected with the shafts, of interlocking sliding bars pivotally connected with the shafts, a collar loosely encircling the bars, and a spring coiled around the bars at each side of the collar and engaging the extremities of the bars, as and for the purpose specified.

2. The combination, with a forward and a rear rock-shaft adapted to be pivotally connected with a wagon-body, of arms projected downward from the rock-shafts, sliding bars pivotally connected with the arms, a collar loosely encircling the bars, a spring coiled around the bars at each side of the collar and engaged by the extremities of the bars, and a connection, substantially as shown and described, between the rock-shafts and the for-

ward and rear axles, as and for the purpose specified.

3. The combination, with a vehicle-body, the forward axle, a forward bolster-bar provided with journal-blocks, and a rear axle also provided with journal-blocks, of rock-shafts journaled in the blocks of the bolster and axle and adapted for pivotal connection with a wagon-body, forked bars pivotally connected with the rock-shafts and held to slide one upon the other, a collar encircling the bars, and a spring coiled around the bars at each side of the collar, the outer ends of the springs being engaged by the outer extremities of the forked bars, as and for the purpose specified.

4. The combination, with a vehicle-body, forwardly and downwardly curved brackets secured to the forward portion of the body, and downwardly and rearwardly curved brackets attached to the rear portion of the body, a forward rock-shaft provided with crank-arms at its extremities pivotally connected with the forward brackets, a rear rock-shaft provided with crank-arms at its extremities having a link connection with the rear brackets, a bolster provided with journal-blocks in which the forward rock-shaft is journaled, and a rear axle provided with boxes in which the rear shaft is journaled, of diagonal plates connecting the bolster and the rear axle, a forward axle pivoted upon the bolster, an apertured hanger secured to the diagonal plates, forked bars held to slide one upon the other through the aperture of the bracket and pivotally connected with the rock-shafts, the outer ends of the forked bars being upwardly curved, and a spring coiled around the sliding bars at each side of the bracket, as and for the purpose specified.
